TOOL KIT

**John N. Petre, Orchard Park, N. Y., assignor to
Park-Metalware Company, Inc., Orchard Park,
N. Y., a corporation of New York**

Application February 12, 1946, Serial No. 646,985.

1 Claim. (Cl. 206—16)

1

This invention relates to an improvement in tool kits of the general type which includes a box for the distribution, display, support and storage of tools provided as a set or series. The invention consists generally in structural details of the box, enabling its cooperation in a novel manner with tool features of the general type to be herein described and also enabling the attainment of the objects set forth below.

The "improved" tool box is adapted to tools of the type which comprise a handle and a shank projecting from and coaxial with the handle and removably fitted thereto; and the tool set comprises shanks provided with tool elements which are suitably differentiated, and a handle common to the shanks, these being adapted for connection to and removal from the handle whereby the several shanks may, from time to time, as occasion may require, be used with such handle. The box has tool supporting features which cooperate in a novel and advantageous manner with projections provided on the shanks and by means of which the shanks may severally be operatively associated with the handle.

Various tools conform to the type described. Examples are screw drivers, socket wrenches and spanners. The kit which is illustrated as an example includes socket wrenches of varying diameters. The composition of the kit is, of course, subject to modification, according to the need or desire of the user; for example, the kit shown includes a series of socket wrenches and a screw driver.

The particular means of connection between the tool shanks and the handle whereby different tool shanks may be interchangeably fitted to the handle may be of any known or suitable construction which includes a projection formed on the shank to enable its operative association with the handle. The construction shown, by way of example, is that which is disclosed in detail in the co-pending application for patent of John N. Petre and John O. Olsen, Serial No. 646,654, now Patent No. 2,476,762, dated July 19, 1949.

The object of the invention is to provide a tool kit wherein the box will have means for the support of two sets of tool shanks severally differentiated in each set, and, if desired, an associated handle for use with any one of the tool shanks of each or both sets, the box when closed will have maximum compactness, and the box has features in such cooperation with the projections on the tool parts as to maintain said parts in a relation such as substantially to eliminate rattles.

ting or marring; the box with the contained tool parts may be conveniently shipped or carried from place to place, and, the box when open, will be available for advertising and sales display, or for the purpose of the use of any, of the tools. Thus when the box is open the display of the tool parts will be complete, attractive and indicative of the manner of use, and the tool parts will be accessible for easy and quick individual removal and replacement, without interference by other parts.

In the accompanying drawings:

Figure 1 is a perspective view of a tool box embodying my invention as closed for the purposes of shipment or of being carried by the workmen from place to place.

Figure 2 is a front elevation thereof as opened for the purposes of display or use.

Figure 3 is a vertical sectional view on the line 3-3 of Figure 2, the box being shown as closed. Figure 4 is a horizontal sectional view along the line 4-4 of Figure 2.

Figure 5 is a fragmentary horizontal sectional view along the line 5--5 of Figure 1.

25. The box comprises companion "half" sections hingedly connected and each including a side wall, the box being opened and closed by relative movements of the sections in book fashion. The side walls 1 and 2 carry sets of tool parts 30. A and B respectively, the construction of the sections and the arrangement of the sets being such that when the box is opened, as shown in Figure 2, any of the tool parts may be freely removed or replaced. The sections are otherwise so constructed as to provide front and rear walls 3 and top and bottom walls 4. The walls 3 and 4 limit the relative closing movements of the sections and effect the complete closure of the box when the side walls are in parallel planes. For convenience of manufacture the front and rear walls 3 are preferably formed as parallel flanges projecting from the longitudinal edges of the side wall 1 and the top and bottom walls 4 are preferably formed as parallel flanges projecting from

45 the transverse edges of the side wall 2. The hinge connections 5 between the half sections of the box directly connect the wall 2 and one of the walls 3. Thus when the sections are positioned to close the box the opposite wall 3 will 50 abut the side wall 2 adjacent its free longitudinal edge and the walls 4 will abut the side wall 1 adjacent its transverse edges. The wall 2 carries adjacent its free edge a pivotally mounted latch finger 6, this finger having a latching lug, 55 which when the wall 2 is closed against the

adjacent front wall 3, may be engaged through a slot 8 in said front wall.

The set A consists of a series of tool shanks 9 of uniform length and arranged in parallel relation, and preferably includes a handle 10 arranged parallel to the shanks 9 and carrying a tool shank 9a which is of the same construction as the shanks 9 and, as above described, is removably fitted in the handle. The shanks are provided at their free ends with any desired tool elements 11. For example, and as shown, the tool elements are socket wrenches graduated in diameters. The shank 9a is similarly provided at its free end with a tool element 11a which may be of any form desired, the form shown being a screw driver. If desired, and as shown, a second series of tool shanks 9b may be arranged at the side of the handle opposite the shanks 9, the shanks 9b being of the same construction as the shanks 9 but being longer whereby they are more suitable for tool elements of the larger sizes. The tool parts of the set A are arranged with their upper ends in close adjacency to the upper end of the half section by which they are carried whereby when the box is open they may be severally removed through the open upper end of the said half section from the positions in which they are normally supported or inserted through said open upper end into the positions in which they are normally supported. The upper end of the handle 10 is substantially in the common plane of the upper ends of the tool elements 11.

The set B consists of a series of tool shanks 12 arranged in parallel relation and preferably includes a handle 13 arranged in parallel relation to the shanks 12 and carrying a tool shank 12a. The tool shanks 12 and 12a are of the same construction as the tool shanks 9 but are of shorter length to enable their use in situations for which the longer tool shanks 9 are not suitable or available. The shanks 12 are provided at their free ends with any desired tool elements 14, these, as shown, being socket wrenches graduated in diameter. The shank 12a is similarly provided at its free end with a tool element 14a which may be of any form desired, the form shown being a screw driver. The set B, in which the tool shanks 12 are of uniform length, is arranged adjacent the lower end of the half section by which it is carried and the length and arrangement of the shanks 12 are such that the upper ends of said shanks, when the box is closed, closely adjoin, but without contacting, the lower ends of the shanks 9. The handle 13 with its attached shank 12a substantially conforms in length to the shanks 12, the upper end of the handle 13 being substantially in the common plane of the upper ends of said shanks. The location of the set B upon the wall 2 is such that when the box is closed the parts composing the set B will be positioned under the shanks 9.

Each of the tool shanks 9, 9a, 9b, 12 and 12a, as an element of the detachable connections between it and the handle, is provided at a suitable distance from its inner end with a projection 15. In the construction shown (which, as above mentioned, conforms to the disclosure of the Petre and Olsen application, Serial No. 646,654) the projections 15 are in the form of splines or keys. The projections 15 cooperate with elements which support the tool parts from the side walls 1 and 2 and hold them in properly centered relation relatively to one another.

The tool supporting elements are designated as 16, 17 and 18 in the order of their cooperation

with the shanks 9, 9b and 12, the shanks 9 being supported by the elements 16, the shanks 9b and the handle 10 and its associated shank 9a being supported by the element 17 and the shanks 12 and the handle 13 and its associated shank 12a being supported by the element 18.

The elements 16, 17 and 18 are similarly constructed, the elements 16 and 17 being rigidly connected in transverse relation to the side wall 1 and the element 18 being rigidly connected in transverse relation to the side wall 2. The elements 16, 17 and 18 are preferably of channel cross section and each include opposing, suitably spaced, upper and lower horizontal flanges 19 and 20, preferably of the same widths as the front and rear walls 3. The opposing flanges 19 and 20 are provided with registering openings 21 through which the shanks are inserted. The projections 15 have supporting engagement upon the upper flanges 19; and the flanges 19 and 20, in opposing pairs, cooperate to hold the shanks in parallel and properly centered relation to one another. The handles 10 and 13 are similarly supported upon the upper flanges 19 and their associated shanks 9a and 12a, respectively, similarly project through registering openings 21 in the opposing flanges whereby the handles are held in parallel and properly centered relation relatively to the adjacent shanks.

The element 18 is preferably of the same extent as the element 16 and has the same number of pairs of registering openings 21 although, as shown, not all of these openings will necessarily be utilized. Thus the elements 16 and 18 may be made from the same die.

Assuming a vertical position of the box for display or use the shanks 9, 9b and 12 are positioned with their tool elements uppermost. When the box is opened, as shown in Figure 2, the bottom wall 4 and the bottom edges of the walls 3 provide stable support for the box upon a counter, work bench or table. Any of the tool parts of the set A may be removed through the open upper end of the half section by which they are carried, the tool parts in such movement being lifted in the axial direction from their supporting element. Similarly any of the tool parts of set B may be removed by being lifted in the axial direction from their supporting element, the space between such tool parts and the top wall 4 being ample to permit such removal. The tool parts of set A are replaced by a movement in the axial direction in which the shanks are passed through the registering openings 21, such movement being continued until the projections 15, or, in the case of the handle, the bottom of the handle engages upon the supporting element. The tool parts of set B are similarly replaced.

The element 18 is so located upon the wall 2 that when the box is closed the tool parts of the set B will have their upper ends under and in closely adjacent relation, and suitably offset relatively to, the lower ends of the shanks 9 as indicated by broken lines in Figure 2. Thus the upper ends of the tool parts of the set B will have contact with the lower ends of the shanks 9 when the box is tilted or inverted, as may happen incidental to transport or storage, and by such contact the displacement of the shanks 12 will be prevented. The adjacency of the upper ends of the shanks 12 to the lower ends of the shanks 9 is of such close degree that the rattling of the shanks 12 will be substantially eliminated. In like manner the upper ends of the shanks 9a and 9b will be adjacent the top wall 4 in a de-

gree of such closeness that displacement of the shanks 9 and 9b will be prevented and the rattling thereof substantially eliminated. Thus the shanks 9 will be positively held in a position in which their lower ends will, as above described, prevent displacement of the shanks 12.

The box thus provides an exceedingly compact container for tool parts of the construction described and, when closed, prevents the displacement of such parts and substantially eliminates their rattling. When open it provides an effective display of the tool parts which may be utilized for advertising or sales purposes and an orderly arrangement thereof which facilitates their proper selection and enables any part to be freely and instantly removed from and replaced into the position in which it is normally supported without interference by any other part.

I claim:

A tool kit comprising a tool box composed of companion half sections hingedly connected for book-fashion opening and closing movement and each including a side wall, the side wall of one section being provided with a top wall which extends in right angular relation, the side walls being in parallel planes when the sections are closed and the top wall, when the sections are closed, bridging the space between the side walls, the section which does not carry the top wall having an open upper end when the sections are opened, tool parts supporting elements mounted transversely upon the side wall of the section which does not carry the top wall and formed with openings having longitudinal axes, an upper set of tool parts having shanks of uniform length, the shanks in each instance being provided with a projection between its ends, the projections being located in the same relative positions on the several shanks, the shanks being fitted in the openings of the tool parts supporting elements whereby the tool parts are maintained in mutually parallel relation and the projections on their shanks have supporting engagement upon the tool parts supporting elements, the supporting elements cooperating with the projections in supporting the tool parts with their upper ends in close adjacency to the open upper end of the section by which the supporting elements

are carried and to the top wall in the closed relation of the sections, other tool parts supporting elements similar to the supporting elements first named and mounted transversely upon the side wall of the section which carries the top wall and at an elevation substantially below the elevation of the tool parts supporting elements first named, a lower set of tool parts having shanks of uniform length and of shorter length than the shanks of the upper set of tool parts, the shanks of the lower set of tool parts in each instance being provided with a projection between its ends, the projections being located in the same relative positions on the several shanks of the lower set of tool parts, the shanks of the lower set of tool parts being fitted in the openings of the second named tool parts supporting elements whereby the tool parts of the second named set are maintained in mutually parallel relation and the projections on their shanks have supporting engagement upon the second named tool parts supporting elements, the second named tool parts supporting elements cooperating with the projections on the shanks of the second named tool parts in supporting the second named tool parts, in the closed relation of the sections, with their upper ends in close adjacency to the lower ends of the shanks of the first named set of tool parts.
